NOZZLE CLOSURE MEANS FOR CONTAINERS
AND WASHERS FOR USE THEREINKarl J. Rolle, Cranston, R. I., assignor to No-
Kap Closures (U. S. A.) Inc., Providence, R. I.,
a corporation of Rhode Island

Application September 19, 1936, Serial No. 101,629

24 Claims. (Cl. 221—60)

My invention relates to improvements in nozzle closure means for containers having an oscillatable valve closure member therein and includes the provision of washer means or a packing member for use between a valve seat provided in the nozzle and said oscillatable valve closure member to provide a more air- and liquid-proof joint than any hitherto provided.

My invention is, in certain respects, an improvement in the type of washer or packing member shown in White 1,967,797 and the type of washer or packing member and closure means described in the joint patent application of James Rest and Albert H. Church, Ser. No. 15 751,734, for Nozzle closure means for containers, and the application of James Rest, Ser. No. 48,043 for improvements in Closures for bottles, collapsible tubes and like containers.

An object of my invention is to provide such a closure means for containers with a positively air- and liquid-tight joint to positively prevent air and liquid seepage through the nozzle closure means. My invention is particularly adapted for use with a nozzle having a partially spherical valve seat therein, dispensing hole means in each end thereof and an at least partially spherical valve closure member oscillatably mounted within said valve seat. For this purpose, I believe I am the first to provide a washer or packing member constructed of compressible material substantially covering the entire surface of the valve seat for the nozzle closure member. A feature of my invention relates to making a washer or packing member in a flat shape which 20 may be readily and quickly bent into a substantially spherical shape for entirely covering the surface of said partially spherical valve seat, which shape is suggestive of a four-leaf clover, namely a center annular portion having a central dispensing hole therein to lie aligned with the dispensing hole in the lower end of the nozzle and a plurality of leaves, in my preferred embodiment four, projecting radially therefrom preferably having convex side walls capable of being bent 25 with said center portion into a partially spherical shape to have the edges thereof substantially abut without overlap when the washer is bent into the partially spherical shape to substantially cover the valve seat.

A further feature of my invention relates to the provision of a washer or packing member provided with a plurality of concentric circular grooves therein whereby the washer or packing member may be more readily flexible, evenly,

without humps or ridges therein, into a partially spherical shape.

A further feature of my invention relates to the provision of a washer or packing member adapted to entirely cover the surface of the substantially spherical valve seat, of flexible compressible material yet provided with a supplemental layer of more compressible material secured on a surface thereof to be compressed between the valve member and valve seat to assist in providing a more air- and liquid-proof closure for said nozzle, which supplemental layer may, if desired, be countersunk within an annular recess in the washer or packing member.

It has been quite difficult to maintain a hollow washer or packing member of this description in alignment with the dispensing holes in the nozzle, and for this purpose I may provide an annular countersink near the lower dispensing hole in the valve receiving recess in the nozzle to receive, if desired, a portion of the annular layer of the more compressible material therein to maintain the washer or packing member center in the desired position within the nozzle; or I may, if desired, provide an annular skirt adapted to overlie the edge of the lower dispensing hole in the nozzle for this centering purpose, which annular skirt may additionally function to overlie and seal the edge of said dispensing hole means if the nozzle be extruded, or otherwise pressure shaped from a blank of coated metal, which is almost impossible to extrude or pressure shape without having the edge of the dispensing means in the lower end of the nozzle expose the metal. Where the base metal of the coated tube comprises lead, it has been believed that a tendency to poison or deleteriously affect the contents of the container exists.

A further object of my invention is to provide a washer or packing member adapted to completely cover the interior surface of the valve seat provided with a skirt to positively overlappingly seal the exposed metal edge in the lower portion of a coated metal nozzle.

These and such other objects of my invention as may be hereinafter appear will be best understood from a description of the accompanying drawings, which illustrate various embodiments thereof.

In the drawings, Fig. 1 is a vertical sectional view through the upper portion of a nozzle closure means for a collapsible tube or other type of container provided with a washer or packing member, both said nozzle closure means and washer or

packing member being constructed in accordance with the principles of my invention.

Fig. 2 is a vertical sectional view of the nozzle closure means shown in Fig. 1 taken along a line 5 at right angles thereto.

Fig. 3 is a reverse plan view of an embodiment of a washer or packing member constructed in accordance with the principles of my invention employing a main washer or packing layer and 10 a supplemental layer of more compressible material countersunk within a recess therein, said main washer or packing layer being constructed with leaves of a shape to be bent into a partially spherical shape without overlap and having 15 grooves characteristic of a feature of my invention.

Fig. 4 is a sectional view taken along the line 4—4 of Fig. 3.

Fig. 5 is a sectional view of the washer or 20 packing member shown in Fig. 4 showing the supplemental layer of more compressible material just prior to being cemented within the suitable countersunk recess therefor in the main washer or packing layer.

Fig. 6 is a diagrammatic perspective view of the 25 washer or packing member shown in Fig. 3 after it has been bent in use into a partially spherical form.

Fig. 7 is an enlarged vertical sectional view 30 taken through the lower portion of the valve member and nozzle with my improved washer or packing member in attached position.

Figs. 8-11 are diagrammatic vertical sectional views illustrating steps in the method I preferably employ of forming and inserting my improved type of washer or packing member within the valve seat, in which Fig. 8 illustrates the step of initially cutting the washer or packing member and starting the bending of the leaves thereof, Fig. 9 illustrates how the top edges of the washer or packing member expand beyond the edges of said shaping hole to be retained in position over the valve seat after the washer or packing member has been inserted through its shaping 40 hole, Fig. 10 illustrates the supplemental step of seating the washer or packing member within the valve seat, and Fig. 11 illustrates the supplemental step of inserting the valve closure member within the valve seat prior to the crimping 45 down of the upper edges thereof over said valve closure member.

Fig. 12 is a diagrammatic plan view looking 50 within the valve seat of the nozzle after the washer or packing member has been seated therein by the step illustrated in Fig. 10.

Figs. 13-17 illustrate various features of a nozzle closure means constructed in accordance with the disclosure in the joint application for patent of Rest and Church, Ser. No. 751,734 employing, however, the plurality of concentric circular grooves on the washer or packing member thereof to provide a more even flexing of said washer or packing member to its desired curved shape; Figs. 19-22 illustrate in comparison 55 there-with a nozzle closure means constructed in accordance with my present invention illustrating the saving in metal therein particularly if a skirt means is employed to maintain the washer or packing member aligned within the valve seat, Figs. 13 and 19, respectively, being side elevations 60 of a collapsible tube constructed in accordance with these two disclosures to illustrate the relative heights of the nozzle closures employed in each; Figs. 14 and 20 being vertical sectional views taken 65 through the respective embodiments; Figs. 15 and

21 being plan views of the types of washers or packing members employed in the respective embodiments; Figs. 16 and 22 being vertical sectional views taken through the respective washers or packing members shown respectively in Figs. 15 and 21 along the respective lines 16—16 and 22—22 thereof; and Figs. 17 and 24 being diagrammatic perspective views of the embodiments of the respective washers or packing members shown in Figs. 15 and 21 after they have been 10 bent into the partially spherical shape characteristic of these types of nozzle closure means.

Fig. 18 is a diagrammatic perspective view similar to Fig. 17 showing what takes place when a non-grooved washer or packing member of the 15 type shown in Fig. 15 is bent into partially spherical shape, spaced humps or ridges appearing in the upper surface of the washer.

Fig. 23 is a vertical sectional view similar to Fig. 22 of an alternative form of washer or packing member constructed in accordance with my 20 invention employing a skirt and constructed of a single layer of washer or packing material.

In the drawings, wherein like characters of reference generally indicate like parts throughout, 25 30 represents a nozzle closure means for a container 32 constructed in accordance with my invention. While I have illustrated my improved type of closure valve means 42 applied to the nozzle 34 of a collapsible tube 32, it is obvious 30 that it may be applied for use in a nozzle of any type of container whether it be a bottle, can, collapsible tube or otherwise. As stated previously, my invention is particularly adapted for use in nozzle closure means for containers of a type 35 comprising a hollow nozzle member 34 having a dispensing hole means 36 in the lower end thereof and a dispensing hole means 38 in the upper end thereof and a partially spherical valve seat 40 therein for receiving the movably, preferably os- 40 cillatably mounted, at least partially spherical 45 valve closure member 42 therein. The nozzle 34 is preferably extruded from a ductile metal but may be otherwise pressure shaped or fabricated from any suitable metal or other material, and the valve closure member 42 is preferably constructed of a thermoplastic composition material, such as synthetic resin or Celluloid, although it may be constructed of metal or any other suitable material, preferably in accordance with the 50 disclosures of the application for patent of James Rest, Ser. No. 678,133, the joint application of Rest and Church, Ser. No. 751,734, and the application of Rest, Ser. No. 48,043. In accordance 55 with the disclosures in said applications, said valve closure member 42 is provided with the diametric recesses or dimples 44 into which portions of the wall of the nozzle may be pressed inwardly as at 48 to form single axis of oscillation forming means for said valve member 42 with the recesses or dimples 44 of said nozzle 34. Said at least partially spherical valve closure member 42 is provided with a vent 46 oscillatable to an open position flush with one or both of said respective dispensing hole means 36 and 38 in 60 the respective lower and upper ends of said nozzle 34 or to a closed position against the side wall of the nozzle 34, and for the purpose of oscillating said valve, it is provided with a projection or turning lug 49 projecting outwardly therefrom 70 through the upper end 38 of said nozzle. If desired, said turning lug 49 may be provided with the concave side walls 50 in accordance with the disclosure of the application of Elton C. Church, Ser. No. 101,967, for Nozzle closure means for 75

containers, bottles, tubes, cans and the like. As stated, Figs. 13-17 illustrate the construction shown in the joint application of Rest and Church, Ser. No. 751,734, in which an annular washer or packing member 52 is interposed between the partially spherical valve seat 40 and said valve member 42, as shown being located in a countersunk recess 54 formed in the lower portion of said valve seat around the lower dispensing hole 36 of said nozzle. I have shown in Fig. 18, however, the ridges 56 which tend to form on such a washer or packing member when bent into the partially spherical formation shown. In order for the washer or packing member 52 or the other types of washers or packing members shown herein or, in fact, any washers or packing members to be able to be easily bent into partially spherical shape without forming said ridges, I preferably provide a plurality of concentric circular grooves 58 therein extending throughout a surface thereof if desired, it being obvious that said grooves 58 may be readily stamped in the washer or packing member during the course of its manufacture. It is thus obvious that when the washer or packing member 52 is bent into a partially spherical shape it will readily flex along the lines of said grooves into the partially spherical shape desired without forming the ridges or humps 56 therein. It is also apparent that in use, if the grooves 58 are formed in the surface of the washer or packing member 52 adjacent the valve 42, the edges thereof will form wiping lines to tend to wipe off any plastic or other material protruding from the end of the discharge vent 46 of said valve after use. In any embodiment of my invention shown, the washer or packing member 52 may be constructed of fabric, leather, rubber or any other suitable resilient material, preferably one which is partially compressible up to at least fifteen thousandths of an inch and preferably one which is relatively stiff and will tend to continuously maintain its set position in use. I preferably, however, construct the improved washers or packing members shown herein of a fabric treated with rubber or any other suitable thermoplastic material or preferably comprising a combination of rubber and cotton fibers as shown in Patents Nos. 1,524,573 and 1,967,529.

A main feature of my invention, however, as previously indicated, is that I preferably construct a washer or packing member 52 not only having an annular center portion 52' constructed of a flexible compressible layer but one provided with an annular layer 60 of more compressible material, such as rubber or latex, secured preferably by a suitable rubber or other cement to a surface thereof, preferably adjacent the inner edge of said portion 52' or annular washer or packing member 52 shown in Figs. 13-17, and as shown in my preferred embodiment, preferably within an annular recess 62 countersunk within, said supplemental washer 60 being thus secured within said recess by means of the cement 64. I believe I am the first, therefore, to provide a washer or packing member comprising two laminated layers, one comprising a standard washer or packing layer of flexible compressible material and the other comprising an annular layer of less width of more compressible material secured on a surface thereof adjacent the inner edge thereof, preferably within a suitable annular countersink or recess therefor provided therein.

As stated hitherto, a main feature of my invention is to provide a washer or packing member or other means completely covering the surface of

the valve seat 40 to protect the valve member 42 from said valve seat and to provide an air- and liquid-proof joint therebetween. My invention therefore includes the provision of a suitable washer or packing member which may be cut or fabricated in flat form so as to be bent without any overlap evenly throughout its area into a substantially spherical shape, and for this purpose, as shown in Figs. 1-11 and 19-24, I have provided a washer or packing member 52 constructed of flexible partially compressible material having an annular center portion 52' having a plurality of leaves 66 projecting radially therefrom preferably of the general shape of a four-leaf clover, said leaves having preferably partially convex side walls and being otherwise cut and fabricated so that said washer or packing member, including said center portion and leaves, may be bent into a partially spherical shape with the edges of said leaves 66 substantially abutting without overlap. If desired, the center portion 52' of my improved washer or packing member may be provided with the supplemental layer 60 of more compressible material secured to a surface thereof adjacent the inner edge thereof, if desired being cemented within an annular countersink or recess 62 therein as shown. If also desired, said leaves 66 or the annular center portion 52', if desired, may be provided with the concentric circular grooves 58 throughout either the upper or lower surface thereof characteristic of my invention to permit the leaves 66 or entire washer or packing member to be readily bent into the partially spherical shape shown in Figs. 6 and 17 without creating the ridges or humps 56.

As stated hitherto, considerable difficulty has been experienced in centering an annular washer or packing member whether it be of the type shown in Figs. 13-17 or of the type shown in the other figures, to have the hole 70 thereof in alignment with the lower nozzle dispensing hole 36, and I may for this purpose provide, if desired, a countersink or recess 54 in the lower portion of the valve seat around said lower dispensing hole 36 as shown in Figs. 1-11, or I may, for centering purposes, provide the center portion 52' of said washer or packing member adjacent said hole with an annular skirt 72 projecting axially therefrom to overlappingly seal the edge of the dispensing hole means 36 in the lower portion of said nozzle, which may expose the metal 74 of a container coated as at 76 extruded or otherwise pressure shaped from a coated blank such as tin coated lead (Fig. 20), and where such a container be provided, exposing the base metal around the edge of said hole 36 as at 75, it is obvious that the skirt shown herein will not only function to center the washer or packing member between the valve seat and valve closure member but will also function to overlappingly seal the exposed base metal edge 75 of said dispensing hole.

I have shown in Figs. 8-11 a suitable form of apparatus for cutting my improved washer or packing member and assembling said washer or packing member and valve member within the nozzle. The center portion 52' of the improved washer or packing member shown in Fig. 4 is first cut with the central hole 70 and leaves 66, if employed, in strip form and then may be provided by pressing or otherwise with the annular countersink 62 continuously in strip form and with the concentric grooves 58 either in the annular center portion 52' thereof and/or throughout said leaves 66. A surface of the more compressible supplemental washer layer 60 may be

coated with a suitable rubber cement 64 and inserted within the countersink 62 or directly to the surface of the center portion 52' thereof if the countersink 62 be not employed. In the embodiment shown, the concentric grooves 58 are preferably pressed, embossed or otherwise formed thereon prior to the washer or packing member 52 being cut out from stock as shown in Fig. 8. The layer of strip material 80 is fed in continuous strip form over a suitable cutting die 82 provided with a hole 84 therein for the center portion 52' having suitable extensions 86 therein complementary to the leaves 66 in the washer or packing member, and a punch 88 therefor also having suitable projections 87 corresponding to the shape of the flat leaves is inserted downwards through said hole 84 in said die 82 to cut the washer or packing member in the shape shown in Fig. 3 from said strip material 80. A suitable folding die 90 having a hole 92 therein is also provided and the upper end of a nozzle 34, provided with a suitable valve seat 40, is placed underneath said hole 92. A plunger 94, having a head 96 shaped to protrude through the hole 70 in said washer or packing member, is forced downwardly through said hole 70 in said washer or packing member forcing the leaves 66 downwardly through the hole 92 in said folding die 90 and within said nozzle 30, the leaves 66 being bent upwardly as shown in Fig. 8 into the position shown in Fig. 9, and after insertion through said hole 92, the leaves 66 may expand outwardly so that the top edges thereof abut the lower surface of said folding die 90 exterior of said hole 92 to retain said washer or packing member loosely within said valve seat. As shown in Fig. 10, a suitable seating die 98 is provided having a flat annular lower surface 100 adapted to force and hold the upper edges of the leaves 66 within said valve seat 40 flush with the upper edge 38 of said nozzle, while the plunger member 102 thereof, having the pilot 104 is lowered within the hole 106 therefor in said seating die 98, said plunger also being provided with a partially spherical seating surface 108 beyond said pilot to compactly and evenly seat the washer or packing member within the valve seat 40, the supplemental layer 60, if employed, being simultaneously forced thereby within said countersink 54 where employed and the edges of the washer or packing member leaves 66 substantially abutting each other without overlap to completely cover the surface of said valve seat 40 as shown diagrammatically in Fig. 12. Fig. 11 diagrammatically illustrates the step of inserting the partially spherical valve closure member 42 within said valve seat 40 after which the edge of the hole 38 in the upper end of said nozzle may be crimped partially over said valve closure member 42 to oscillatably secure it within said valve seat 40 in accordance with the disclosure in the joint application of Rest and Church, Ser. No. 751,734, heretofore referred to.

It is thus obvious that I have provided a novel type of nozzle closure means for containers and novel types of washers for use therein with the advantages explained above.

It is understood that my invention is not limited to the specific embodiments shown and that various deviations may be made therefrom without departing from the spirit and scope of the appended claims.

What I claim is:

1. A packing member comprising a flexible compressible layer having an annular center por-

tion having an annular recess on a surface thereof or near the inner edge thereof, said center portion having a plurality of leaves projecting radially therefrom having convex side walls capable of being bent with said center portion and with the edges of said leaves substantially abutting without overlap into a partially spherical shape, said leaves having a plurality of concentric circular grooves therein throughout a surface thereof and an annular washer of more compressible material secured within said recess. 5 10

2. A packing member comprising a flexible compressible layer having an annular center portion having a plurality of leaves projecting radially therefrom having side walls capable of being bent with said center portion and with the edges of said leaves substantially abutting without overlap into a partially spherical shape. 15

3. A packing member comprising a flexible compressible layer having an annular center portion having an annular recess on a surface thereof or near the inner edge thereof, said center portion having a plurality of leaves projecting radially therefrom having side walls capable of being bent with said center portion and with the edges of said leaves substantially abutting without overlap into a partially spherical shape and an annular washer of more compressible material secured within said recess. 20 25

4. A packing member comprising a flexible compressible layer having an annular center portion having a plurality of leaves projecting radially therefrom having convex side walls capable of being bent with said center portion and with the edges of said leaves substantially abutting without overlap into a partially spherical shape. 30 35

5. A packing member comprising a flexible compressible layer having an annular center portion having a plurality of leaves projecting radially therefrom having side walls capable of being bent with said center portion and with the edges of said leaves substantially abutting without overlap into a partially spherical shape, said leaves having a plurality of concentric circular 40 45

grooves therein throughout a surface thereof. 50

6. A packing member comprising a flexible compressible layer having an annular center portion having a plurality of leaves projecting radially therefrom having convex side walls capable of being bent with said center portion and with the edges of said leaves substantially abutting without overlap into a partially spherical shape, said leaves having a plurality of concentric circular 55

grooves therein throughout a surface thereof and an annular layer of more compressible material secured on a surface of said annular center portion near the inner edge thereof. 60

7. A packing member comprising a flexible compressible layer having an annular center portion having a plurality of leaves projecting radially therefrom having side walls capable of being bent with said center portion and with the edges of said leaves substantially abutting without overlap into a partially spherical shape, and an annular layer of more compressible material secured on a surface of said annular center portion near the inner edge thereof. 65

8. A packing member comprising a flexible compressible layer having an annular center portion having a plurality of leaves projecting radially therefrom having convex side walls capable of being bent with said center portion and with the edges of said leaves substantially abut- 70 75

ting without overlap into a partially spherical shape, and an annular layer of more compressible material secured on a surface of said annular center portion near the inner edge thereof.

5 9. A packing member comprising a flexible compressible layer having an annular center portion having a plurality of leaves projecting radially therefrom having side walls capable of being bent with said center portion and with the edges of said leaves substantially abutting without overlap into a partially spherical shape, said leaves having a plurality of concentric circular grooves therein throughout a surface thereof and an annular layer of more compressible material secured on a surface of said annular center portion near the inner edge thereof.

10 10. A packing member comprising a flexible compressible layer having an annular center portion having a plurality of leaves projecting radially therefrom having side walls capable of being bent with said center portion and with the edges of said leaves substantially abutting without overlap into a partially spherical shape, said center portion having an annular skirt projecting axially from the inner edge thereof.

15 11. A packing member comprising a flexible compressible layer having an annular center portion having a plurality of leaves projecting radially therefrom having convex side walls capable of being bent with said center portion and with the edges of said leaves substantially abutting without overlap into a partially spherical shape, said leaves having a plurality of concentric circular grooves therein throughout a surface thereof and an annular layer of more compressible material secured on a surface of said annular center portion near the inner edge thereof, said center portion having an annular skirt projecting axially from the inner edge thereof.

20 12. A flexible annular compressible washer having an annular recess on a surface thereof near the inner edge thereof and an annular washer of more compressible material secured within said recess.

25 13. A flexible annular laminated washer comprising a flexible layer and an annular layer of more compressible material of less width secured to a surface thereof adjacent the inner edge thereof.

30 14. Nozzle closure means for a container comprising a hollow nozzle member having dispensing hole means in each end thereof and a partially spherical valve seat therein, an at least partially spherical closure valve member oscillatably mounted on said valve seat having a vent oscillatable to positions flush with said respective hole means or against said side wall and a turning lug projecting outwardly from said nozzle to oscillate said closure valve member, and a packing member covering the entire surface of said valve seat having a portion thereof countersunk within said valve seat.

35 15. Nozzle closure means for a container comprising a hollow nozzle member having dispensing hole means in each end thereof and a partially spherical valve seat therein, an at least partially spherical closure valve member oscillatably mounted on said valve seat having a vent oscillatable to positions flush with said respective hole means or against said side wall and a turning lug projecting outwardly from said nozzle to oscillate said closure valve member, and a packing member covering the entire surface of said valve seat.

40 16. Nozzle closure means for a container com-

prising a hollow nozzle member having dispensing hole means in each end thereof and a partially spherical valve seat therein, an at least partially spherical closure valve member oscillatably mounted on said valve seat having a vent 5 oscillatable to positions flush with said respective hole means or against said side wall and a turning lug projecting outwardly from said nozzle to oscillate said closure valve member, and a packing member covering the entire surface of said valve seat having the lower portion thereof covered 10 covered with a layer of more compressible material and countersunk within said valve seat.

15 17. Nozzle closure means for a container comprising a hollow nozzle member having dispensing hole means in each end thereof and a partially spherical valve seat therein, an at least partially spherical closure valve member oscillatably mounted on said valve seat having a vent oscillatable to positions flush with said respective hole 20 means or against said side wall and a turning lug projecting outwardly from said nozzle to oscillate said closure valve member, and a packing member covering the entire surface of said valve seat having the lower portion thereof covered 25 with a layer of more compressible material.

20 18. Nozzle closure means for a container comprising a hollow nozzle member having dispensing hole means in each end thereof and a partially spherical valve seat therein, an at least partially spherical closure valve member oscillatably mounted on said valve seat having a vent oscillatable to positions flush with said respective hole 25 means or against said side wall and a turning lug projecting outwardly from said nozzle to oscillate said closure valve member, said valve seat having a countersink therein surrounding the dispensing hole means in the lower end thereof and a packing member contained between said valve seat and closure valve member having an 30 annular center portion having an annular layer of more compressible material secured to the lower surface thereof within said countersink adjacent the dispensing hole means in the lower end of said nozzle, said annular center portion 35 having a plurality of integral leaves projecting radially therefrom bent upwardly with said center portion to have the edges of said leaves substantially abut without overlap into a partially spherical shape completely covering said valve 40 seat.

45 19. Nozzle closure means for a container comprising a hollow nozzle member having dispensing hole means in each end thereof and a partially spherical valve seat therein, an at least partially spherical closure valve member oscillatably mounted on said valve seat having a vent oscillatable to positions flush with said respective hole means or against said side wall and a turning lug projecting outwardly from said nozzle to oscillate 50 said closure valve member, and a packing member contained between said valve seat and closure valve member having an annular center portion adjacent the dispensing hole means in the lower end of said nozzle, said annular center 55 portion having a plurality of integral leaves projecting radially therefrom bent upwardly with said center portion to have the edges of said leaves substantially abut without overlap into a partially spherical shape completely covering 60 said valve seat.

55 20. Nozzle closure means for a container comprising a hollow nozzle member having dispensing hole means in each end thereof and a partially spherical valve seat therein, an at least partially 65

- spherical closure valve member oscillatably mounted on said valve seat having a vent oscillatable to positions flush with said respective hole means or against said side wall and a turning lug projecting outwardly from said nozzle to oscillate said closure valve member, said valve seat having a countersink therein surrounding the dispensing hole means in the lower end thereof and a packing member contained between said valve seat and closure valve member having an annular center portion within said countersink adjacent the dispensing hole means in the lower end of said nozzle, said annular center portion having a plurality of integral leaves projecting radially therefrom 5

21. Nozzle closure means for a container comprising a hollow nozzle member having dispensing hole means in each end thereof and a partially spherical valve seat therein, an at least partially spherical closure valve member oscillatably mounted on said valve seat having a vent oscillatable to positions flush with said respective hole means or against said side wall and a turning lug projecting outwardly from said nozzle to oscillate said closure valve member, and a packing member contained between said valve seat and closure valve member having an annular center portion having an annular layer of more compressible material secured to the lower surface thereof adjacent the dispensing hole means in the lower end of said nozzle, said annular center portion having a plurality of integral leaves projecting radially therefrom bent upwardly with said center portion to have the edges of said leaves substantially abut without overlap into a partially spherical shape completely covering said valve seat.
22. Nozzle closure means for a container comprising a hollow nozzle member having dispensing hole means in each end thereof and a partially spherical valve seat therein, an at least partially spherical closure valve member oscillatably mounted on said valve seat having a vent oscillatable to positions flush with said respective hole means or against said side wall and a turning lug projecting outwardly from said nozzle to oscillate said closure valve member, and a packing member contained between said valve seat and closure valve member having an annu-

lar center portion adjacent the dispensing hole means in the lower end of said nozzle, said annular center portion having a plurality of integral leaves projecting radially therefrom bent upwardly with said center portion to have the edges of said leaves substantially abut without overlap into a partially spherical shape completely covering said valve seat, said center portion having an annular skirt projecting axially therefrom to overlap the edge of said dispensing hole 10 means in the lower end of said nozzle.

23. Nozzle closure means for a container comprising a hollow nozzle member constructed of coated metal having dispensing hole means in each end thereof, the edge of which exposes said metal, and an inner wall substantially comprising a substantially spherical valve seat, an at least partially spherical closure valve member oscillatably mounted on said valve seat having a vent oscillatable to a position flush with said 20 respective hole means or against said nozzle inner wall and a projection projecting outwardly from said nozzle to oscillate said closure valve member and a partially spherical packing member comprising an annular portion contained 25 between the lower portions of said valve seat and oscillatable valve member having an annular skirt projecting downwardly within said container overlappingly sealing the edge of the dispensing hole means in the lower portion of said 30 nozzle, said annular portion having a plurality of leaves projecting radially therefrom having side walls bent upwardly with said center portion and with the edges of said leaves substantially abutting without overlap into a partially spherical shape completely covering said valve seat.

24. Nozzle closure means for a container comprising a hollow nozzle member having dispensing hole means in each end thereof and a partially spherical valve seat therein, an at least partially spherical closure valve member oscillatably mounted on said valve seat having a vent oscillatable to positions flush with said respective hole means or against said valve seat and a turning lug projecting outwardly from said nozzle to oscillate said closure valve member, said valve seat having a countersink therein surrounding the dispensing hole means in the lower end thereof and a flexible packing member having a plurality of preformed concentric circular grooves 45 throughout a surface thereof bent to lie within said countersink in arcuate formation therein.
